UNITED STATES PATENT OFFICE.

WILLIAM AITKEN, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,338,350.

Specification of Letters Patent. Patented Apr. 27, 1920.

Application filed March 20, 1917. Serial No. 156,070.

To all whom it may concern:

Be it known that I, WILLIAM AITKEN, a subject of the King of Great Britain, and resident of Marconi House, Strand, London, 5 England, have invented a new and useful Improvement in Telephone Systems, of which the following is a specification.

My invention relates to automatic and semi-automatic telephone systems, and particularly to improvements in trunking systems to increase the efficiency of working between different switching stages in large systems, and at the same time to reduce the cost particularly on systems using simple 15 relays for switching and connecting.

The important features of my invention are:—

1. The provision of connecting means associated with each subscriber's line, so that 20 connection can be obtained with one of a plurality of different outgoing and incoming lines.

2. By the above means and the system of 25 multiplied trunks which is the subject of my co-pending application Serial No. 156,069, Patent No. 1,311,432, July 29, 1919, the inter-connecting of large groups of lines, such as subscribers' lines, with the total incoming and total outgoing trunk lines necessary for 30 the traffic of the said large group of lines.

3. In known systems, the accessibility from and to adjacent lines is generally limited between 10 and 18, usually the former. My system is only limited by the number of 35 trunks in a group. For example, if there are 60 trunks, subscribers 0 to 59 can all be talking simultaneously; if 500 trunks, then 500 adjacent lines can be connected.

4. Following on the above, the following 40 facilities hitherto deemed essential are now unnecessary:—

(a) No intermediate distributing facilities are necessary to equalize the traffic between the subscribers' lines and the trunks.

45 (b) Secondary pre-selectors are unnecessary, and the primary pre-selectors may be of smaller capacity.

5. The number of trunk lines necessary to carry a given traffic can be reduced (owing 50 to the large size of the groups), and the number of trunks can be increased without alteration in the wiring of the switches.

6. Multiplied trunks make it possible now, by the aid of suitable intermediate connecting means described below, to connect a large 55

group of lines, such as 1000 subscribers' lines, to the total incoming trunks necessary to carry the traffic of the group.

7. The incoming accessibility to 1000 subscribers introduces new methods of building 60 up a connection, which with other new improvements are described later.

The invention covers particularly the effective use of the subscriber's line switch in relation to outgoing and incoming trunk 65 working, and the arrangement is therefore described in connection with three-digit calling, that is, having a capacity of 999 lines. The system may, however, be extended to any size by a corresponding use of similar 70 arrangements and apparatus, preferably with incoming trunks having access to outgoing trunks only.

Each subscriber's line is fitted with the usual line and cut-off relays, and in addition 75 with a group of connecting relays according to the traffic requirements. Five will be sufficient for the average exchange. Preferably the connecting relays have two armatures, one to be attracted by a current of a 80 certain strength, and the other by a stronger current. The former is preferably used for incoming calls and the latter for outgoing calls, to allow of the registering meter being actuated by a further increase of current when required. These relays carry the necessary springs to connect a subscriber's line to either an incoming or an outgoing trunk as required.

The connecting relays are used in combination with auxiliary means to bring about connection between a calling line and an idle outgoing or incoming trunk. Such means, which determine the idle line to be connected, are well known either utilizing relays or in an electromechanical form. In one form of my invention I use a momentary circuit closing device which closes one at a time a plurality of circuits initially to energize the connecting means. This interrupter, as it may be called, may be continuously driven, or be controlled by the energization of the calling line relay in a well known manner. In another form of my invention I use the known circuit determining arrangement described in Bygrave's specification Serial No. 132884, Patent No. 1,269,903, June 18, 1918.

At intermediate and final digit switching stages the two-armature relays are used 110

in a somewhat different manner. On the switch connecting the incoming trunks to the multiplied intermediate lines on the subscribers' line switches, for example, each 5 relay can connect an intermediate line to one or other of two incoming trunks according as one or both armatures are attracted.

The intermediate lines are multiplied over the incoming springs of the line 10 switches according to my co-pending application, and at the other end terminate in the main circuit of a switch which may be of the electro-mechanical type. Preferably two-armature relays are associated with the 15 intermediate lines, as many as may be necessary for the traffic between a group of incoming trunks and a group of subscribers, two lines being connected by each relay. The number of intermediate lines equals the 20 number of incoming trunks and the latter are multiplied over all the switches of the intermediate lines, so that any intermediate line can connect with any incoming trunk.

Each incoming trunk has associated with 25 it a three-digit impulse responder, preferably individual to the line. The responder is electro-mechanical, and a shaft rises and falls for each set of impulses, a different wiper, however, connecting in a different 30 bank of contacts for each rise. The first rise connects up a relay controlling access to a particular group of 100 lines, the second rise controls access to a group of 10 lines, and the last connects with the particular 35 subscriber called, to cause his line to connect with the calling incoming trunk over an intermediate line.

The outgoing lines are multiplied over the line switch also, according to my co-pending 40 application.

My invention is illustrated by the accompanying drawings in which:—

Figure 1 is a single line key or schematic diagram;

Fig. 2 shows more particularly the subscriber's line switch;

Fig. 3 shows the intermediate line connecting switch;

Fig. 4 shows a method of opening the 50 common wiring connections on a line switch.

Fig. 5 shows a relay line switch with the circuit determining arrangement according to Bygrave's specification Patent No. 1,269,903. Figs. 6 and 7 show details.

Fig. 1 shows a subscriber's line *a* having access to 5 outgoing trunks *b* by a line switch *f*, the outgoing trunks at their other end being multiplied at *c* over switches *d* associated with the intermediate lines *e* 55 multiplied over the incoming springs of the subscriber's line switch *f*.

In Fig. 2 the series of relays C1 to C5 constitutes the line switch *f*, the five outgoing junctions OJ1 to OJ5 correspond to 60 the outgoing trunks *b* and the incoming

junctions IJ1 to IJ5 correspond to the intermediate lines *e*. In Fig. 3 the series of relays *d* correspond to the switches *d* and the lines incoming at the top left hand corner correspond to the multiples *c*. In these 70 figures also the double armatures are represented as secured together and capable of moving between two contacts, and it is to be supposed that when any relay is energized by a weaker current the armature moves toward it and when it is energized by the stronger current the armature moves away from it. The construction and mode of operation of these C relays are described below with reference to Figs. 6 and 7.

The circuits and operation of Fig. 2 are as follows:—

Circuit 1.—Subscriber lifts receiver to call; line relay L energized.

Circuit 2.—Momentary circuit completed 85 over moving circuit closer CC; relay C5 energizes. (If OJ5 is engaged, C5 deenergizes and C4 energizes, and so on, each connecting relay C energizing in turn).

Circuit 3. (Figs. 2 and 3).—Cut-off relay 90 COR energizes in series with meter M and relay R3 and second winding of C5 (meter does not energize).

Circuit 4.—COR and M are now connected in parallel to circuit 3, L being cut 95 off. R3 energizes and introduces resistance *r*₃ to reduce current. *r*₃ can be short-circuited to cause meter to operate in well known manner. Another calling circuit being momentarily connected by the circuit 100 closing device in parallel with this now engaged circuit will not be affected, as COR having its windings in series, is shunted by the engaged line low resistance cut-off winding. The current will not be sufficient to 105 energize COR, the C relay in series will not retain, and the interrupter will connect up the next C relay.

Circuit 5.—Extended line circuit in which R5 Fig. 3, energizes.

Circuit 6.—Guarding relay R6 energizes and connects battery in parallel by 3' to line 3.

The caller now sends impulses of three-digits, R5 deenergizing for each opening of 115 the circuit. R6 being slow to release, does not deenergize. In Fig. 3, an electro-mechanical or stepping form of impulse responder is shown, the shaft rising for each digit impulse with the wipers or contact springs *W* not making contact. After a series of impulses, a magnet WR presses a wiper *W* into contact with a spring or plate *S* to complete a momentary circuit, after which the shaft falls and rises again on the 120 next series of impulses. The relays RS1 etc. connect the succeeding relays WR in circuit. The wipers *W* are for the sake of clearness shown diagrammatically to the left of the 125 rack RS; they are in reality carried by it as 130

shown in the right bottom corner of Fig. 2.

Circuit 7.—The first opening of the circuit at the sub-station causes R5 to deenergize and R7 to energize.

Circuit 8.—Relay R8 then energizes. R7 and R8 are both slow to release.

Circuit 9.—R5 deenergizing also energizes the lifting magnet LR to lift the rack or shaft RS one step, the release magnet Re1 holding it in that position between impulses. I will assume that the rack has been lifted nine steps, and, in the interval between the first and second digit, relay R5 is energized and R7 and then R8 deenergize.

Circuit 10.—R7 completes a momentary circuit before R8 deenergizes and WR1 energizes to press wiper W1 against contact S1.

Circuit 11.—R11 then energizes. R11 may be common to a plurality of responders.

Circuit 12.—Retaining circuit of R11.

Circuit 13.—Circuit completed by WR1 to energize RS1.

Circuit 14.—Retaining circuit of RS1.

Circuit 15.—R8 deenergizing completes a circuit to energize the release magnet when shaft or rack RS falls to normal position and opens the release circuit.

The impulses of the second digit lift shaft RS again, and R7, R8 are again energized on the deenergization of R5.

Circuit 16.—R7 deenergizing after the impulses extends circuit 10 to the second wiper magnet WR2 to cause the wipers to make contact with S2 (assuming the second digit to be also 9).

Circuit 17.—Circuit 10, 16 is then extended so that R17 (Fig. 2) is energized.

Circuit 18.—Retaining circuit of R17.

Circuit 19.—RS2 is energized to extend the energizing circuit as before.

Circuit 20.—Retaining circuit of RS2.

R8 deenergizing energizes Re1 so that shaft again falls and Re1 circuit is opened. On the third set of impulses R7 and R8 again energize and shaft RS is lifted. At the termination of the series (9 again assumed).

Circuit 21.—R7 deenergizes and circuit 10, 16 is extended to energize WR3 to cause the wipers to make contact.

Circuit 22.—The circuit is then extended to energize the called party's line relay L.

Circuit 23.—Retaining circuit of L. The interrupter CC now energizes the relays C of the called party one after the other through the resistance r7, so that one armature only is attracted.

I will assume that the intermediate line connected to C2 is idle.

Circuit 24.—Momentary energizing circuit of C2.

Circuit 25.—Third conductor circuit of intermediate line completed through COR

as for circuit 3. R25 (Fig. 5) energizes. COR energizing engages the line as described for an outgoing call.

Circuit 26.—RS3 energizes.

Circuit 27.—RS3 retained over 27, 20, 14. 70 R8 deenergizing releases the shaft as before.

Circuit 28.—RS1, RS2, RS3 in combination with R25 complete a circuit to energize a connecting relay R28 to connect the idle intermediate line to the calling incoming 75 trunk.

Circuit 29.—Circuit 25 is now cut off from R25 and extended to the holding or guarding circuit of the incoming trunk in which R29 is energized. R29 energizing 80 opens circuit 14 so that the RS relays deenergize to release the responder, and cuts off the parallel battery connection from circuit 3.

After conversation, R5 deenergizes, then 85 R6 so that the guarding circuit is opened between the time R6 and R29 deenergize to release all relays in the circuit. If relay R28 had been energized over resistance r29, one armature only would have been attracted and a different trunk connected.

The circuit has been described in connection with the same subscriber's line unit for incoming and outgoing connections, for the sake of simplifying the drawing. It is of 95 course to be understood that two line switches are involved in a connection. Circuit 5 is the outgoing trunk extending over the line switch to the calling line and incoming at the impulse relay.

Circuit 30. is the talking circuit of the intermediate line which at one end is multiplied over a plurality of subscribers' line switches as described in my co-pending application, and at the other end terminates 105 in a plurality of relays over which the incoming trunks are multiplied.

Fig. 4 shows a modification to insulate the circuits to the interrupter normally.

Circuit 31.—A wire common to a group 110 is connected to each line relay so that when a line relay is energized, a plurality of two-armature relays is energized to pull up a light armature of each.

Circuit 32.—Circuits completed to the interrupter, the interrupter then pulling up the second armatures in turn to connect a plurality of lines to relays C to earth (circuit 33) the calling line relays C only being energized.

In Fig. 5 two two-armature relay switches are shown, each associated with a subscriber's line, each switch consisting of 115 5 relays Cc giving access to 5 outgoing and 5 incoming trunks. In addition, each subscriber's line has the usual line and cut-off relays (L1 and CO respectively). Each line has also either a two-armature relay S or two single armature relays S1, S2, to switch into the circuit relays Cc, so that either one 120 125 130

or both armatures are attracted to connect up either a plurality of incoming or outgoing trunk third-conductor circuits to the circuit-determining relays CD to energize initially 5 a particular relay Cc on an idle trunk, as disclosed in Bygrave's specification Serial No. 132884.

The circuits and operation of apparatus are as follows:—

10 *Circuit 41.*—Subscriber lifts receiver to call, relay L energizes.

Circuit 42.—Relay S energizes to pull up both armatures, or S2 energizes.

15 *Circuit 43.*—Battery is connected in parallel to all relays Cc of a line.

Circuit 44.—Outgoing trunks TO1 to TO5 third conductors are extended to circuit-determining relays CD (which may be common to 10 lines). Relays CD and the trunks 20 associated therewith are engaged from CD1 upward, and if I assume CD1 and CD2 lines busy, CD3 will energize and

25 *Circuit 45.*—In conjunction with circuit 43 completes the initial energizing circuit of connecting relay Cc3.

Circuit 46.—Relay CO energizes over extended third conductor circuit RO3 with a retaining winding of Cc3 in series.

30 *Circuit 47.*—The subscriber's line is thus extended to an outgoing trunk BO3, AO3. Relay L1 deenergizes, S or S2 deenergizes, and the initial energizing circuits are opened so that the line cannot be interfered with.

35 *Incoming calls.*

Circuit 48.—The impulse responder, after receiving the trains of impulses, completes a circuit to energize relay S to pull up one 40 armature, or energizes S' in the case of line B.

Circuit 49.—Battery is then connected through resistance r to the common side of the initial energizing windings of relay Cc.

Circuit 50.—The third conductors of incoming trunks T11 to T15 are extended to the circuit-determining relays CD. If lines 1 to 5 are busy, CD5 will energize.

50 *Circuit 51.*—The initial energizing circuit of relay Cc5 to pull up one armature. The cut-off relay energizes and the wanted line is extended to the incoming trunk as before described.

55 The relays C may be of the type shown in Figs. 6 and 7, consisting of a coil 63 surrounding an iron core 66. The magnetic return 64 is brought to the front to a point in line with the core and on this

60 two armatures 65 and 67 are suspended. The armature 67 may be made lighter than 65 and placed nearer the core to render it more sensitive to weak currents. One group of springs 60, 61, 62, is shown, but it will 65 be readily understood that a plurality of

groups may be similarly fitted. The armature 67 has an insulated stud 68 which forms a stop or rest for spring 60, and the ends of the U-shaped armature 65 are bridged by a strap 70 which carries an insulated stud 69 forming a stop or rest for the spring 61.

70 When a small current is passed through the coil 63, the armature 67 will be attracted to the core 66 and the spring 60 (which may be thinner than the other two) will be forced into contact with spring 61. When a greater current is passed through coil 63 the armature 65 will also be attracted to the core 66 and spring 61 will be lifted from 80 spring 60 into contact with spring 62. In the latter condition both armatures are operated but in the following description for the sake of simplicity the armature is spoken of as being operated when a heavy 85 current is passed through the coil, the lighter armature not then doing any effective work.

What I claim is:—

1. In a telephone system, the combination 90 of a line, a plurality of relays associated with said line, a set of lines connected to terminals of said relays, another set of lines connected to other terminals of said relays, means for causing the relays to connect the line with an idle line of one set and means for causing the relays to connect the line with an idle line of the other set.

2. In a telephone system, the combination 100 of a line, a plurality of relays, each having two armatures, associated with said line, a set of lines connected to terminals of said relays, another set of lines connected to other terminals of said relays, means for causing one armature of a relay to be operated to connect the line with an idle line of one set and means for causing the other armature to be operated to connect the line with an idle line of the other set.

105 3. In a telephone system, the combination 110 of a line, a plurality of relays, each having two armatures, associated with said line, and a plurality of pairs of lines, one armature of each relay being adapted to connect the line to one of a pair and the other armature adapted to connect the line to the other of the same pair.

115 4. In a telephone system, the combination 120 of a line, a plurality of relays associated with the line, each relay having two armatures, a set of lines connected to terminals of said relays, a second set of lines connected to other terminals of said relays, means for energizing the relays by a current to cause the armature of a relay to connect the line to an idle line of one set and means for energizing the relays by a stronger current to cause the other armature of the relay to connect the line to an idle line of the other set.

5. In a telephone system, the combination of a line, a plurality of pairs of lines, a plurality of relays each having two armatures, one adapted to connect the line to one line of a pair and the other adapted to connect the line to the other line of the pair, a device adapted to close momentarily one after the other the circuits of the relays on one side, and a relay associated with the line and adapted to close such circuits on the other side. 50
6. In a telephone system, the combination of a line, a plurality of pairs of lines, a plurality of connecting relays each having two armatures, one adapted to connect the line to one line of a pair and the other adapted to connect the line to the other line of the pair, a device adapted to close momentarily one after the other the circuits of the connecting relays on one side, a relay associated with the line and adapted to close such circuits on the other side, a cut-off relay and means whereby, when a connecting relay on an idle line is energized, a retaining circuit is established through the cut-off relay. 60
7. In a telephone system, the combination of a line, a plurality of pairs of lines, a plurality of connecting relays each having two armatures, one adapted to connect the line to one line of a pair and the other adapted to connect the line to the other line of the pair, a device adapted to close momentarily one after the other the circuits of the connecting relays on one side, a relay associated with the line and adapted to close such circuits on the other side, a cut-off relay and means whereby, when a connecting relay on a busy line is energized, the cut-off relay is prevented from energizing and, on the device passing to the next connecting relay, the former connecting relay is caused to deenergize. 70
8. In a telephone system, the combination of a line, a plurality of pairs of lines, a plurality of relays each having two armatures, one adapted to connect the line to one line of a pair and the other adapted to connect the line to the other line of the pair, a device adapted to close on one side an initial energizing circuit of the relay associated with an idle line and a relay associated with the line and adapted to close such circuit on the other side. 75
9. In a telephone system, the combination of a line, a plurality of pairs of lines, a plurality of connecting relays each having two armatures, one adapted to connect the line to one line of a pair and the other adapted to connect the line to the other line of the pair, a device adapted to close momentarily one after the other the circuits of the connecting relays on one side, a relay associated with the line and adapted to close such circuits on the other side, a double wound cut-off relay having its windings normally in series, means for energizing the cut-off relay and means for retaining it through its two windings in parallel. 80
10. In a telephone system, the combination of a subscriber's line comprising a third conductor, an incoming line, an outgoing line, a double wound relay having two armatures, a resistance, means for passing a current through one winding of the relay so as to cause one armature to connect the line with the outgoing line, means for inserting the resistance in the energizing circuit so as to cause the other armature to connect the line with the incoming line and means for connecting the other winding to the third conductor. 85

In testimony that I claim the foregoing as my invention, I have signed my name this 28th day of February, 1917.

WILLIAM AITKEN.
